J. D. JOYCE

WINDING MACHINE

Filed June 27, 1925

Patented May 25, 1926.

1,585,865

UNITED STATES PATENT OFFICE.

JAMES DANIEL JOYCE, OF PHILADELPHIA, PENNSYLVANIA.

WINDING MACHINE.

Application filed June 27, 1925. Serial No. 39,980.

This invention relates in general to winding machines, and more particularly to machines for winding double taper ended cops for use in loom shuttles and the like, such a machine being disclosed in my co-pending applications, Serial No. 710252 filed May 1, 1924, Serial No. 710253 filed May 1, 1924, and Serial No. 710254 filed May 1, 1924.

Machines of this type are used to wind cops with tapered ends and a cylindrical body. The winding is started with substantially cylindrical layers which gradually progress forward and overlap each other to build a conical face, upon which subsequent layers are wound to form the cylindrical body of the cop. The progression in layers is effected through the gradual feeding of the thread guide along its traverse rod as the winding proceeds.

The taper of the nose of such a cop is governed by a shaper which controls the position of the contact or progression wheel with relation to the spindle or cop during the process of the winding of the heel of the cop. Heretofore, it has been the practice to provide a traverse rod of two or more parts, one of which has a mounting which permits it to be moved by contact of a portion of the thread guide assembly with a shaper, laterally forward or away from the spindle during the winding of the heel of the cop. This lateral movement causes the progression wheel to contact with the yarn being wound and causes that earlier progression of the wheel necessary to the building of a tapered heel.

It is an object of my invention to provide a novel and improved means for supporting the progression wheel adjustably with relation to the spindle of the winding machine. This adjustable supporting means for the progression wheel includes means for supporting the said wheel upon the traverse rod in such a manner as to permit of motion of the wheel eccentric of the said rod toward and away from the spindle.

It is another object of my invention to provide means for normally holding said progression wheel concentric of said traverse rod.

Other objects of my invention are to be found in the accompanying specification and claims, and will be disclosed in the accompanying drawings in which:

Figure 1 is a plan view of my device, with portions broken away, showing my

movably mounted progression wheel in its normal position.

Figure 2 is a similar view to that shown in Figure 1, except that the progression wheel is shown in the position nearest the spindle.

Figure 3 is a vertical cross section on the line 3-3 of Figure 2.

Figure 4 is an end elevation of the structure shown in Figure 2.

Figure 5 shows in detailed perspective the parts of my composite progression wheel assembly.

Figure 6 is a detailed perspective view of a straddle spring cooperating with the progression wheel and guide rod thereof.

Referring now with greater particularity to the drawings, it will be seen that my device is comprised as follows.

The winding machine is of the type shown in the co-pending applications above referred to and has the usual frame 1, rotating spindle 2 and traverse bar 3. The traverse bar 3 has a screw-threaded forward portion 3^a adapted to be secured to the usual means for its reciprocation and a rearward portion 3^b fixedly though detachably secured thereto and having a sliding bearing 9 in the frame 1. The traverse bar has suitable bearings 4 and 5 in the frame 1 and is secured to a second rod 6 having a bearing 7 in the frame and carrying a shaper 8 longitudinally and rotatably adjustable as described in my co-pending applications.

Mounted on the rod 3^a is a bushing 10 having a portion thereof cut away to provide an extension 11 in which a semi-cylindrical groove 12, the purpose of which will be described hereinafter, is cut. The bushing 10 has fixedly secured thereto, by means of a set screw 13, a collar 14. A washer 15 is mounted on said bushing to space the collar 14 from a shaper contact member 15'. The member 15' has an arm 16 terminating in an arcuate face 17 adapted to contact with the conical shaper 8 to control the taper of the heel of the cop. The member 15' has a second arm 18 terminating in a forked end adapted to straddle a leaf spring 19 mounted on suitable rollers 20 on a rod 21 which parallels the axis of the spindle. The member 15' is mounted in the bushing 10 and has a substantially U-shaped bore 27; the bend of the U being semi-cylindrical and the arms being tangential thereto.

The outer surface of the member 15' is

cylindrical to provide a bearing for the progression wheel 22 which is mounted thereon on a bushing 23. The bushing 23 has an upstanding flange 24 provided with 5 a pin 25 adapted to extend through an aperture 26 in the wheel 22 for securing the said wheel to its bushing. It is obvious that the bushing 23, the wheel 22 and the member 15' are fixed together and will move 10 in unison. The U-shaped bore 27 permits these members to have a limited motion eccentric of the rod 3^a and the bushing 10.

A bushing 30, provided with a smooth bore, is also mounted on the rod 3^a. This 15 bushing has a disk 31 formed integrally therewith of a diameter suitably less than that of the progression wheel. The ends of this bushing are cut to provide grooves 32 and 33 and collars 32^a and 33^a. Just forward of the disk 31 the bushing 30 has a portion cut away to permit a single toothed gear 34 to extend therethrough to engage the threads of the screw on the rod 3^a to provide 20 for the progression of the guide. The gear 25 34 is pivotally secured to the disk 31 and is held normally in contact with the thread of the rod 3^a by means of a leaf spring 35. This gear may be released from contact with the rod by pressing the forwardly extending portion 36 thereof toward the barrel of the 30 bushing.

The disk 31 has also a radially extending slot 37 in which the pin 25 is adapted to slide when the progression wheel is moved laterally. It is obvious that though the progression wheel may be moved laterally, the pin 25 and slot 37 insure that any rotative movement of the progression wheel will result in 35 rotation of the disk 31 and hence, through 40 the medium of the gear 34, cause movement of the disk along the rod.

The rearward end of the bushing 30 is adapted to be slipped in the open end of the U-shaped bore 27 and slid toward the center 45 of the bore until the collar 32^a fits within the groove 12 and prevents relative endwise movement between the bushings 10 and 30.

A thread guide 40 is pivotally mounted on the rod 3^a through means of a thread guide 50 carrier arm 41. The arm 41 is mounted on a bushing 42 and straddles a second bushing 43 similarly mounted and carrying an arm 44 one end of which terminates in a finger 45 adapted to limit the movement of the 55 guide away from the spindle and the other end of which terminates in a forked shaped end which straddles the rod 21.

The arm 41 has a cutaway portion 46 to 60 provide an arcuate finger 47 for engagement with the collar 33^a and the groove 33. This locks the thread guide carrier arm and the progression wheel assembly against relative endwise movement and insures that the 65 thread guide moves with the progression wheel in endwise directions. When the

parts of the thread guide carrier arm and the progression wheel assembly are arranged concentrically in order the rod 3^a is inserted and acts as a lock holding all of the parts together, the bushing 10 being held to the 70 bushing 30 by the parts 32 and 12, and the thread guide carrier arm being locked to the bushing 30 by the members 33 and 47.

An arm 48 having an arcuate end 49 is fixed to the arm 41 and adapted to contact 75 with a collar 50 on a rod 51 to operate a stop mechanism as has been described in my prior applications.

From the foregoing the operation of my device will be seen to be as follows. At the 80 commencement of the winding the gear is pressed out of engagement with the thread of the rod and the thread guide assembly moved back to the point of the beginning of the winding. As this assembly is 85 moved backward the arcuate face 17 of the arm 16 comes in contact with the face of the conical shaper 8 and forces the progression wheel 22 over toward the spindle against the action of the spring 19 on the arm 18, the 90 bushing riding with its U-shaped slot on the extension of bushing 10. The gear is then released to engage the threads of the rod 3^a and the progression wheel remains in this position until a sufficient number of turns 95 have been wound to cause the wheel to engage the yarn on the cop. This contact results in the wheel being rotated, the action causing, through the medium of the gear, a progressive movement of the guide. As the 10 progressive movement continues the arm face 17 rides out along the conical shaper permitting the wheel to be moved outward from the spindle under the influence of the leaf spring 19 toward its normal position concentric with the rod 3^a. Obviously this progressive movement results in the building of 10 a cop with a tapered heel or base. Once the face 17 is free of the shaper, the building of the cop will proceed in such a manner that 11 its body is cylindrical. When the winding is complete, the face 49 of the arm 48 contacts with the collar 50 and the machine is stopped.

Having described my device in detail, I 11 wish to claim:

1. In a winding machine, the combination with the winding spindle, traverse-bar, thread guide and means to reciprocate the traverse-bar and thread-guide, of means 12 mounted on said bar and capable of movement transversely thereof to feed the guide along the bar and longitudinally and rotatively adjustable means to regulate the feeding of the guide to determine the taper of 12 the base of the package wound.

2. In a winding machine, the combination of a rotating spindle, a reciprocating traverse-bar, means to rotate the spindle and means to reciprocate the bar, a thread-guide 12

5 mounted on the bar, a wheel mounted on said bar and capable of movement transversely thereof to feed the thread-guide along the bar and means cooperating to adjust the 10 wheel in lateral relation to the winding spindle and the bar as the winding increases in diameter.

10 3. In a winding machine, the combination of a rotating spindle, a reciprocating traverse-bar, means to rotate the spindle and means to reciprocate the bar, a thread-guide mounted on the bar, a wheel mounted on said bar and capable of movement transversely thereof to feed the guide along the 15 bar, and means cooperating to hold the wheel eccentric of said bar in close proximity to the winding spindle at the beginning of the winding and to adjust the wheel away from the winding spindle towards its position 20 concentric of said bar as the cop increases in diameter.

25 4. In a winding machine, the combination of a rotating spindle, a reciprocating traverse-bar, means to rotate the spindle and means to reciprocate the bar, a thread-guide mounted on the bar, a wheel mounted on said bar and capable of movement transversely thereof to feed the guide along the bar, and means cooperating to hold the wheel eccentric 30 of said bar in close proximity to the winding spindle at the beginning of the winding and spring means to move the wheel away from the winding spindle towards its position 35 concentric of said bar as the cop increases in diameter.

40 5. In a winding machine, the combination of a rotating spindle, a reciprocating traverse-bar having a portion thereof screw threaded, means to rotate said spindle and means to reciprocate said bar, a thread guide mounted on the bar, a bushing having a gear adapted to engage the threads of said bar, and a thread guide secured to said bushing in such 45 a manner as to prevent relative endwise movement, a progression wheel mounted on said bar and capable of movement transversely thereof adapted to contact with the winding on the cop to rotate said bushing to propel said guide along said bar, and means 50 cooperating to adjust said wheel eccentrically of said bar in lateral relation to the winding spindle according to the growing diameter of the cop being wound.

55 6. In a winding machine, the combination of a rotating spindle, a traverse-bar arranged to reciprocate longitudinally of the spindle, means to rotate the spindle and means to reciprocate the bar, a thread-guide mounted on the bar, means to feed the guide along the bar, including a progression wheel mounted on said bar and capable of movement transversely thereof adapted to contact with the winding, and means cooperating to 60 move the wheel on said bar laterally to ad-

just the progression wheel toward or away from the winding spindle according to the diameter of the winding.

7. In a winding machine, the combination of a rotating spindle, a reciprocating traverse-bar, means to rotate the spindle and means to reciprocate the bar, a thread-guide mounted to travel along the bar, a wheel mounted on said bar and capable of movement transversely thereof adapted to contact with the cop to feed the guide along the bar, means cooperating to move said wheel eccentrically of said bar toward the winding spindle to bring the wheel in close proximity thereto during the beginning of the winding, and means to return the bar to its normal position concentric of said bar as the cop increases in diameter.

70 8. In a winding machine, the combination with a rotating spindle and a reciprocating thread-guide, means to rotate the spindle and means to reciprocate the thread-guide, of means engaged by the cop to feed the guide progressively along the spindle from the beginning to end of the winding, said means being movable eccentrically of said bar laterally toward and away from the winding spindle to shape the base end of the cop.

75 9. In a winding machine, the combination with a rotating spindle, of a reciprocating traverse-bar capable of movement transversely thereof, a progression wheel mounted on said bar and normally held concentrically thereof, and a plurality of means cooperating to move said wheel eccentrically of said bar toward and away from said rotating spindle.

80 10. In a winding machine, the combination with a rotating spindle and a reciprocating traverse-bar, means to rotate the spindle and means to reciprocate the bar, of a thread-guide mounted on the bar, a progression wheel mounted on said bar and capable of movement transversely thereof adapted to contact with the winding at the rear end of each traverse of the bar to feed the thread-guide along the bar, means cooperating to hold the progression wheel closely adjacent the winding spindle eccentrically of said bar at the beginning of the winding, and yielding means to move the progression wheel gradually away from the winding spindle as each layer of yarn is wound on the cop until the latter reaches its predetermined diameter.

85 11. In a winding machine, the combination with a winding spindle, a reciprocating traverse-bar, and means to reciprocate the bar, of a thread-guide mounted on the bar to oscillate to and from the winding spindle, a progression wheel mounted on said bar and capable of movement transversely thereof adapted to be turned to feed the thread-guide along the bar, and means 90

cooperating to automatically adjust the wheel eccentrically of said bar laterally toward and away from the winding spindle to contact with the largest diameter of each 5 layer of winding.

12. In a winding machine, in combination, a rotating spindle and reciprocating traverse-bar, means to rotate said spindle and means to reciprocate said bar, a thread-guide holder pivotally mounted on said bar, a progression wheel mounted on a bushing on said bar and adapted to contact with the winding on the cap to feed the guide holder along the bar said wheel being capable of 10 movement eccentric of said bar, a shaper, an arm on said bushing adapted to contact with said shaper to move said wheel eccentrically of said bar toward said winding spindle in position to contact with the first 15 layers of the winding, and means to return said wheel to its proper position concentric of said bar as the winding progresses.

13. In combination, for use in winding machines having a rotating spindle and a screw-threaded reciprocating traverse-bar, a bushing having a grooved semi-circular extension mounted on said rod, a contact member mounted on said bushing and having a U-shaped recessed bore, a progression 25 wheel rotatably mounted on said contact member and movable laterally therewith, a progression nut locked with said bushing against relative endwise motion and with said wheel against relative rotative movement and a thread-guide holder movable along said bar by said progression nut.

14. In combination, for use in winding machines having a rotating spindle and a screw-threaded reciprocating traverse-bar, a bushing having a grooved semi-circular extension and mounted on said rod, a contact member mounted on said bushing and having a U-shaped recessed bore, a progression wheel rotatably mounted on said contact 30 member and movable laterally therewith, a progression nut locked with said bushing against relative endwise motion, a pin in said wheel having a sliding fit in a slot in said nut to prevent relative rotational movement while permitting relative lateral movement of said wheel with respect to said nut, and a thread guide holder movable along said bar by said progression nut.

15. In combination, for use in winding

machines having a rotating spindle and a screw-threaded reciprocating traverse-bar, a bushing having a grooved semi-circular extension and mounted on said rod, a contact member mounted on said bushing and having a U-shaped recessed bore, a progression wheel rotatably mounted on said contact member and movable laterally therewith, a progression nut locked with said bushing against relative endwise motion, a pin in said wheel having a sliding fit in a slot in said nut to prevent relative rotational movement while permitting relative lateral movement of said wheel with respect to said nut, and a thread guide holder movable along said bar by said progression nut, and means whereby said bar acts as a locking means for securing said bushing, contact member, progression wheel, progression nut, and a thread guide holder in their assembled positions.

16. In a winding machine, the combination of a spindle, a thread guide, a thread guide holder, a reciprocating bar supporting the guide carrier, and automatic means mounted on said bar and capable of movement transversely thereof for feeding said carrier along said bar, a portion of said automatic means being movable eccentrically on said bar.

17. In a winding machine, the combination of a spindle, a thread guide, a thread guide holder, a reciprocating bar supporting the guide carrier, and automatic means mounted on said bar and capable of movement transversely thereof for feeding said carrier along said bar, a portion of said automatic means being movable eccentrically on said bar, and a former controlling said eccentric movement.

18. In a winding machine, the combination of a spindle, a thread guide, a thread guide holder, a reciprocating bar supporting the guide carrier, and automatic means movable eccentrically and transversely on said bar for feeding said carrier along said bar, and a conical former adapted to be engaged by a finger on said automatic means to move said automatic means eccentrically and transversely of said rod toward and away from said spindle.

In testimony whereof I affix my signature.

JAMES DANIEL JOYCE.
